UNITED STATES PATENT OFFICE

169,970

POWDER DISPENSING CAN

Ernest W. Freeman, Belleville, N. J., assignor to
Continental Can Company, Inc., New York,
N. Y., a corporation of New York

Application March 17, 1953, Serial No. 24,058

Term of patent 14 years

(Cl. D58—17)

To all whom it may concern:

Be it known that I, Ernest W. Freeman, a citizen of the United States and a resident of Belleville, County of Essex and State of New Jersey, have invented a new, original, and ornamental Design for a Powder Dispensing Can, of which the following is a specification, reference being had to the accompanying drawing, forming a part hereof.

Fig. 1 is a perspective view of a powder dispensing can showing my new design;

Fig. 2 is a plan view thereof on an enlarged scale and

Fig. 3 is a side view in elevation thereof taken on an enlarged scale.

I claim:

The ornamental design for a powder dispensing can, as shown.

ERNEST W. FREEMAN.
